UNITED STATES PATENT OFFICE.

ROBERT C. WADE, OF HICKORY PLAINS, ARKANSAS.

HORSE-POWER.

SPECIFICATION forming part of Letters Patent No. 225,445, dated March 9, 1880.

Application filed December 11, 1879.

To all whom it may concern:

Be it known that I, ROBERT C. WADE, of Hickory Plains, in the county of Prairie, and in the State of Arkansas, have invented certain new and useful Improvements in Horse-Powers; and I do hereby declare that the following is a full, clear, and exact description thereof, reference being had to the accompanying drawing, and to the letters of reference marked thereon, making a part of this specification.

The nature of my invention consists in the construction of a horse-power for cotton-gins and other purposes, as will be hereinafter more fully set forth.

In order to enable others skilled in the art to which my invention appertains to make and use the same, I will now proceed to describe its construction and operation, referring to the annexed drawing, which represents a perspective view of my improved horse-power.

A represents a frame of any suitable construction, or it may be the room in which the power is placed. In this frame is a vertical shaft or roller, B, turning in suitable bearings at top and bottom, and having a large band-wheel, C, secured to it, said wheel being braced by means of inclined braces D, running from near the periphery of the wheel downward and inward to the roller. Below these braces two horizontal arms, E E, are framed into the roller, and extend on a line in opposite directions.

Two inclined braces, F F, and two parallel levers, G G, are framed together and to the

arms E E, substantially in the manner shown, and a platform, H, connects the levers. At the ends of the levers G G are hooks a a, or their equivalents, for connecting the horses.

By this construction, as shown and described, the following advantages are derived: It saves one driver, and is more easily driven by one driver than the old one is by two, because he is in reach and can drive both teams at once. The arrow-shaped bracing, as described, is a compact arrangement for strengthening or supporting the horse levers or sweeps. Further, the convenience of having breast-chains on one team is safe and easily attached, and will save accidents in the event of the belts running off or breaking.

The whole power is so thoroughly bolted and framed together that the motion and movement are regular and even.

Having thus fully described my invention, what I claim as new, and desire to secure by Letters Patent, is—

In a horse-power, the arrow-shaped bracing consisting of the arms E E, levers G G, and inclined braces F F, as described, in combination with the vertical shaft B, wheel C, and the braces D, substantially as herein shown and described.

In testimony that I claim the foregoing I have hereunto set my hand this 27th day of November, 1879.

ROBERT CHARLES WADE.
